HIP SPLINT

Jesse E. Hawley, Warsaw, Ind., assignor to Zimmer Manufacturing Company, Warsaw, Ind.

Application November 11, 1935, Serial No. 49,275

15 Claims. (Cl. 128—84)

This invention relates to surgical appliances such as are used in the reduction and immobilization of broken legs and hip and pelvis bones.

The invention has special reference to a device 5 of this character wherein a sound hip is used as the means to fixedly support the appliance in traction producing relation to the injured member, a counter-traction or compression stress being produced at the sound hip. The invention is, 10 therefore, preferably termed a hip splint.

One important object of the invention is to provide a novel device of this character by the use of which a fracture may be reduced and immobilized without removal of the patient from 15 his bed and by the doctor or surgeon alone, other skilled assistance being unnecessary.

A second important object of the invention is to provide a novel appliance of this character which, when in use, does not require the patient 20 to lie in prone position since he may move between prone and reclining positions without disarranging the splint or reducing traction on the injured leg.

The traction produced by this splint is preferably skeletal traction, a Steinman pin being employed for this purpose.

A third important object of the invention is to provide a novel device of this character wherein provision is made for applying equal traction to 30 both ends of the pin.

A fourth important object of the invention is to provide a novel spring arrangement for permitting relative adjustment of the well hip and injured leg parts during application of the splint.

With the above and other objects in view as 35 will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is a perspective view of the novel 45 appliance, the Steinman pin being shown in one position in full lines and in a second position in dotted lines.

Figure 2 is a vertical section on the plane 2—2 of Figure 1.

Figure 3 is a detail elevation showing the manner of adjusting a certain cross bar connecting the well leg and injured leg parts, so that the cross bar is disposed at an angle to the well hip.

In the embodiment of the invention as herein disclosed there is provided for the well leg a stir-

rup consisting of a pair of side members 10. An arm 11 is securely riveted to the inner side of the side members and these two arms are arranged in lapping relation, one arm lying flat on top of the other. Longitudinal slots 12 are formed 5 in the arms 11 and register so that securing bolts 13 may be passed through these slots, the bolts being provided with wing nuts 14. By tightening the nuts the arms 11, which form the bottom of the stirrup, are fixed in adjusted relation. Thereby the side members 10 may move adjustably toward and from each other and be secured in adjusted position.

The side members 10 extend below the stirrup bottom and are provided with vertically spaced 15 holes 15 to receive bolts 16 provided with wing nuts 17. These holes 15 in each side member are provided so that the bolts 16 may be selectively positioned on the side members.

A cross bar 18 is provided, adjacent one end, 20 with a pair of aligned slots 19 through which the bolts 16 pass, the nuts 17 serving to clamp the cross bar in adjusted position to the side members 10. The slots 19 permit three different kinds of adjustment between the side members and 25 cross bar. First, these slots permit the adjustment of the side members 10 toward and from each other. Second, the stirrup may be adjusted bodily along the bar. Third, the stirrup and cross bar may be adjusted, as in Figure 3, to various angular relations. Of course, any two or all 30 of these adjustments may be effected at the same time, the nuts 17 clamping the parts in whatever positions of adjustment are effected between the stirrup and cross bar.

Fixed to the other end of the cross bar is an angle bracket 20 wherethrough passes a pin 21. A second angle bracket 22 is provided with a slot 23 wherethrough the pin 21 passes, the cross bar and second bracket being thus pivotally and slidably connected. These angle brackets have parallel horizontal arms and a rod 24 connects these arms and is slidably mounted in at least one arm. A spring 25 surrounds the rod 24 and urges the brackets apart so that the pin 21 normally engages the upper end of the slot 23.

Fixed to the lower end of the bracket 22 is a stirrup bar 26 having sleeves 27 extending upwardly at each end. Through the bar and these sleeves pass sleeve nuts 28 which have knurled 50 heads 29 below the bar. In these sleeves are screwed the shanks of long traction screws 30 which have their upper ends bent to form T-heads 31 whereon are slidably and revolvably mounted pin holders 32 in the form of cylin- 55

drical blocks having suitable openings for the T-heads 31. Set screws 33 are fitted in the upper ends of the pin holders 32 and engage the T-heads 31 to fix the pin holders in desired adjusted positions. Also these pin holders are provided with suitable openings to receive the end portions of a Steinman pin 34.

In using the splint the side members 10 are adjusted to the desired distance apart and there 10 held by the nuts 14 and bolts 13. The nuts 17 are loosened to permit this adjustment. The stirrup formed by the members 10 and 11 is now attached to the well leg by a suitable plaster cast. Next the pin 34 is inserted through a bone 15 of the fractured leg at a point selected by the surgeon or doctor and there held by a suitable bandage or plaster cast so that its ends project. The pin holders are now fitted on the ends of the pin, being loosened to slide and revolve on the 20 T-heads for this purpose and the heads being raised or lowered by manipulation of the screw sleeves 28 by their knurled heads 29. At the same time the cross bar 18 is adjusted and secured. In doing this it may be necessary to 25 compress the spring 25. When the parts are all adjusted to suit the requirements of the case they are fixed in adjustment by tightening the thumb screws 33 and nuts 17. The knurled heads 29 are now turned to apply whatever tension 30 is necessary to reduce the fracture, the screws 30 being held from rotation by their connection through the pin carriers with the pin. When the doctor is satisfied that the fracture has been reduced and proper traction exists a 35 plaster cast is applied to hold the second stirrup and to immobilize the injured leg.

There has thus been provided a simple and efficient device of the kind described and for the purpose specified.

40 It is obvious that minor changes may be made in the form and construction of the invention without departing from the material spirit thereof. It is not, therefore, desired to confine the invention to the exact form herein shown and described, but it is desired to include all such as 45 properly come within the scope claimed.

Having thus described the invention, what is claimed as new, is:

1. In a splint of the kind described, a positioning stirrup, an injured leg stirrup, a bar fixed to the first stirrup and connecting said stirrups, said second stirrup having rigid side members 50 adjustable for length, screw means to adjust the lengths of said side members independently, pin holders mounted on the upper ends of said second stirrup sides the upper ends of said second stirrup sides being provided with means for 55 slidable and rotatable adjustment of the pin holders, and means to secure the pin holders in adjusted position.

2. In a splint of the kind described, a positioning stirrup, an injured leg stirrup, a bar fixed to the first stirrup and connecting said stirrups, said second stirrup having side members 60 adjustable for length, means to adjust the lengths of said side members independently, T-heads on the upper ends of the said sides of the second stirrup, pin holders slidably and rotatably adjustable on said T-heads, and means to 65 secure the pin holders to the T-heads in adjusted positions.

3. In a splint of the kind described, a positioning stirrup, an injured leg stirrup, a bar fixed to the first stirrup and connecting said 70 stirrups, said second stirrup having side members

adjustable for length, means to adjust the lengths of said side members independently, T-heads on the upper ends of the said sides of the second stirrup, pin holders slidably and rotatably adjustable on said T-heads, and means to 5 secure the pin holders to the T-heads in adjusted positions, said T-heads being arranged for swivelling movement on the axes of the stirrup sides to accommodate the positions of the pin 10 holders.

4. In a splint of the kind described, a positioning stirrup including spaced sides and an extensibly adjustable bottom member, means to secure the extensible member in adjusted position, an injured leg stirrup having rigid sides 15 adjustable independently for length and screw means to so adjust said last sides, pin holders mounted on the upper ends of the last sides, and a bar fixed immovably to the first stirrup and having the second stirrup connected thereto. 20

5. In a splint of the kind described, a positioning stirrup including spaced sides and an extensibly adjustable bottom member, means to secure the extensible member in adjusted position, an injured leg stirrup having rigid sides 25 adjustable independently for length and screw means to so adjust said last sides, pin holders mounted on the upper ends of the last sides, and a bar fixed immovably to the first stirrup and having the second stirrup connected thereto by a pin 30 and vertical slot connection.

6. In a splint of the kind described, a positioning stirrup including spaced sides and an extensibly adjustable bottom member, means to secure the extensible member in adjusted position, 35 an injured leg stirrup having sides adjustable independently for length and means to so adjust said last sides, pin holders mounted on the upper ends of the last sides, a bar fixed immovably to the first stirrup and having the second 40 stirrup connected thereto by a pin and vertical slot connection, and a spring associated with the pin and slot connection to hold the second stirrup normally depressed with respect to the bar.

7. In a splint of the kind described, a positioning stirrup including spaced sides and an extensibly adjustable bottom member, means to secure the extensible member in adjusted position, 45 an injured leg stirrup having sides adjustable independently for length and means to so adjust said last sides, T-heads on the upper ends of said extensible sides, pin holders slidably and rotatably adjustable on said T-heads, means to 50 secure the T-heads in adjusted positions, and a bar fixed immovably to the first stirrup and having the second stirrup connected thereto.

8. In a splint of the kind described, a positioning stirrup including spaced sides and an extensibly adjustable bottom member, means to secure the extensible member in adjusted position, 60 an injured leg stirrup having sides adjustable independently for length and means to so adjust said last sides, T-heads on the upper ends of said extensible sides, pin holders slidably and rotatably adjustable on said T-heads, means to 65 secure the T-heads in adjusted positions, and a bar fixed immovably to the first stirrup and having the second stirrup connected thereto by a pin and vertical slot connection.

9. In a splint of the kind described, a positioning stirrup including spaced sides and an extensibly adjustable bottom member, means to secure the extensible member in adjusted position, 70 an injured leg stirrup having sides adjustable independently for length and means to so adjust 75

said last sides, T-heads on the upper ends of said extensible sides, pin holders slidably and rotatably adjustable on said T-heads, means to secure the T-heads in adjusted positions, a bar fixed immovably to the first stirrup and having the second stirrup connected thereto by a pin and vertical slot connection, and a spring associated with the pin and slot connection to hold the second stirrup normally depressed with respect to the bar.

10. In a splint of the kind described, a positioning stirrup including spaced sides and an extensibly adjustable bottom member, means to secure the extensible member in adjusted position, an injured leg stirrup having sides adjustable independently for length and means to so adjust said last sides, T-heads on the upper ends of said extensible sides, pin holders slidably and rotatably adjustable on said T-heads, means to secure the T-heads in adjusted positions, said T-heads having swivelling movement on the axes of the extensible sides to accommodate the positions of the pin holders, and a bar fixed immovably to the first stirrup and having a second stirrup connected thereto.

11. In a splint of the kind described, a positioning stirrup including spaced sides and an extensibly adjustable bottom member, means to secure the extensible member in adjusted position, an injured leg stirrup having sides adjustable independently for length and means to so adjust said last sides, T-heads on the upper ends of said extensible sides, pin holders slidably and rotatably adjustable on said T-heads, means to secure the T-heads in adjusted positions, said T-heads having swivelling movement on the axes of the extensible sides to accommodate the positions of the pin holders, and a bar fixed immovably to the first stirrup and having a second stirrup connected thereto by a pin and vertical slot connection.

12. In a splint of the kind described, a positioning stirrup including spaced sides and an extensibly adjustable bottom member, means to secure the extensible member in adjusted position, an injured leg stirrup having sides adjustable independently for length and means to so adjust said last sides, T-heads on the upper ends of said extensible sides, pin holders slidably and rotatably adjustable on said T-heads, means to secure the T-heads in adjusted positions, said T-heads having swivelling movement on the axes of the extensible sides to accommodate the positions of the pin holders, a bar fixed immovably

to the first stirrup and having a second stirrup connected thereto by a pin and vertical slot connection, and a spring associated with the pin and slot connection to hold the second stirrup normally depressed with respect to the bar.

5

13. In a splint of the kind described, a positioning stirrup including spaced sides and an extensibly adjustable bottom member, means to secure the extensible member in adjusted position, an injured leg stirrup having sides adjustable independently for length and means to so adjust said last sides, T-heads on the upper ends of said extensible sides, pin holders slidably and rotatably adjustable on said T-heads, means to secure the T-heads in adjusted positions, a cross 15 bar, means to fix one end of the cross bar immovably in desired longitudinal and angular adjustment to the first stirrup, and a connection between the other end of the cross bar and the second stirrup.

20

14. In a splint of the kind described, a positioning stirrup including spaced sides and an extensibly adjustable bottom member, means to secure the extensible member in adjusted position, an injured leg stirrup having sides adjustable 25 independently for length and means to so adjust said last sides, T-heads on the upper ends of said extensible sides, pin holders slidably and rotatably adjustable on said T-heads, means to secure the T-heads in adjusted positions, a cross 30 bar, means to fix one end of the cross bar immovably in desired longitudinal and angular adjustment to the first stirrup, and a pin and slot connection between the other end of the cross bar and the second stirrup.

35

15. In a splint of the kind described, a positioning stirrup including spaced sides and an extensibly adjustable bottom member, means to secure the extensible member in adjusted position, an injured leg stirrup having sides adjustable 40 independently for length and means to so adjust said last sides, T-heads on the upper ends of said extensible sides, pin holders slidably and rotatably adjustable on said T-heads, means to secure the T-heads in adjusted positions, a cross- 45 bar, means to fix one end of the cross bar immovably in desired longitudinal and angular adjustment to the first stirrup, a pin and slot connection between the other end of the cross bar and the second stirrup, and a spring associated 50 with the pin and slot connection to hold the second stirrup normally depressed with respect to the bar.

JESSE E. HAWLEY.
